UNITED STATES PATENT OFFICE

MERRILL M. BLACKBURN, OF DAVENPORT, IOWA

SCORE CARD HOLDER

Application filed May 16, 1928. Serial No. 278,071.

The present invention pertains to holding means for score cards and more particularly to such a holder for golf score cards, the same being adapted for easy attachment to and detachment from a golf bag.

Among the objects of this invention are to provide a score card holder of the character indicated which will be efficient for the purpose stated; to provide a golf score card holder which will be readily attachable to and detachable from a golf bag; to provide a structure of the character indicated which can be easily and cheaply manufactured and which can be sold at a reasonable price; to provide a structure of the character indicated which has associated therewith or forming a part thereof means to hold a suitable marking instrument, such as a lead pencil; and such further objects, advantages and capabilities as will hereafter appear and as are inherent in the construction disclosed. My invention further resides in the combination, construction and arrangement of parts illustrated in the accompanying drawings and while I have shown therein what is now considered the preferred embodiment of said invention, together with a modification thereof, I desire the same to be understood as illustrative only and not as limiting said invention.

In the drawings attached hereto and forming a part hereof of Fig. 1 is an elevation of a holder having a score card attached thereto; Fig. 2 is a longitudinal section of the construction shown in Fig. 1 substantially along the plane indicated by the line 2—2 in said figure, a portion of a golf bag being shown in dotted lines; Fig. 3 is a fragmentary section of a modification of the structure shown in Figs. 1 and 2; Fig. 4 is a fragmentary transverse section substantially along the plane indicated by the line 4—4, Fig. 1.

Referring more in detail to the annexed drawings, numeral 1 denotes a sheet or plate of somewhat rigid material such as sheet iron, sheet aluminum, fiber and the like. I prefer to make this of sheet aluminum. This plate has its corners rounded as indicated at 2 so that the person and clothing of the user will not be injured thereby. As indicated

at 3, the upper end is extended slightly, primarily for the purpose of improved appearance. The extremity of this portion of the plate is extended and bent over as indicated at 4 to form an attaching tab 5 whereby a suitable clamp 6 may be attached by means of a rivet or rivets 7, or the like. The clamp 6 here illustrated is a well-known clamp readily procurable on the market and the same is equipped with a pair of handles 8 by means of which the jaws 9 of the clamp may be separated. To attach this device to a golf bag or the like the jaws of the clamp are separated by means of the handles 8 in a well-known manner and then they are slipped over the edge 10 of the bag with the plate 1 outside thereof and resting against the outer surface of the bag. The clamp is then permitted to close and, preferably, the arm 8 inside of the bag is turned down to rest against the inside thereof.

A score card 11 is placed under the jaw which is outside of the bag and between it and the plate 1. This can be accomplished by pressing both of the handles 8 together to open the jaws 9 or by pressing inwardly on the outer handle 8 when the latter is turned up into the customary opening position. It will be noted that the angle at 4 between the plate or sheet 1 and the tab 5 is an acute angle. It is preferred to make this angle substantially the same as the corresponding angle of the clamp 6 so that the jaw 9 will fit closely against the plate or against a card inserted between the plate and the jaw. If desired, the plate can be bent substantially at a point in line with the edge of the jaw so that the plate will have the same direction as the median plane of the clamp, that is, the direction of a plane passing through the rivets 7 and midway between the jaws 9. If this be constructed in this manner, the clamp will then occupy a slightly different direction upon the bag. However, this is not considered as any improvement over the shape shown in Fig. 2. If desired, more than one card can be inserted between the plate and jaw 9 but, ordinarily, one is all that will be desired.

In the modification shown in Fig. 3, the

end of the plate 1 is turned up as indicated at 12 to form a flange 13 between which and the plate 1 the lower end of the card 11 may be inserted in order to prevent the card from 5 being bent or torn during use.

As indicated in Figs. 1 and 4, the edge of the plate may be slotted at 14 and 15 and then alternate tongues may be bent in opposite directions as indicated at 16 and 17. 10 These are curved as shown most clearly in Fig. 4 and form a clamp for the reception of a marking element such as a pencil 18. When this marking element is inserted between the tongues 16 and 17 it is normally shoved 15 lengthwise into the space between them. To withdraw the pencil, it may be either drawn out longitudinally or pulled laterally to cause the tongues to spread apart. In order to do this, it is necessary that the material of the 20 plate 1 have a certain amount of resiliency so that it will return to shape sufficiently to hold the pencil in place. It will be seen from this disclosure that the lower tongue 17 will serve as a guard to protect the point of the 25 pencil. If additional protecting means is desired, the lower portion of this tongue may be sufficiently enlarged so that it can be rolled over to form a complete or substantially complete tube into which the point of the pencil 30 projects. This would slightly increase the cost of material and manufacture but might correspondingly increase the desirability of the article.

If it were considered desirable, a scale 35 could be marked along one edge of the plate in any desired manner as by pressing scale lines into the material or marking them thereon. It is quite common to have a six inch scale marked along one edge of score 40 cards. This scale mentioned as being applied to the plate 1 could take the place of the score card scale, in event the cards were not printed with such a scale.

Score cards are made in various sizes and 45 shapes and it will therefore be understood that these holders will probably be also made in a variety of sizes and shapes.

While I have shown herein what is now considered the preferred embodiment of my 50 invention, it will be understood that various departures from this disclosure may be made without departing from the spirit thereof.

Having now described my invention, I 55 claim:

55 1. In a holder of the character indicated, a plate having an edge thereof bent over at an angle to the body thereof, to serve as means whereby a clamp may be secured to the plate, a somewhat U-shaped clamp having the 60 part thereof remote from its open side secured to the bent over part and having one of its jaws on each side of the plate, arranged to receive between themselves and opposite sides of the plate articles to be held 65 by the clamp.

2. A holder of the character indicated comprising a substantially flat body having an edge thereof bent over at an angle to the body, a clamp at said edge having a jaw upon each side of said body, each jaw being adapted to hold an article between itself and the body, and said jaws being resiliently connected to each other by a cross-member, the cross-member being connected to the bent-over edge, and a pencil holder formed in another portion of said body, said clamp having operating arms pivotally connected to its jaws. 70

3. In a holder of the character indicated, a plate having an edge thereof bent over at 80 an angle to the body thereof, to serve as means whereby a clamp may be secured to the plate, a somewhat U-shaped clamp having the part thereof remote from its open side secured to the bent over part and having one 85 of its jaws on each side of the plate, arranged to receive between themselves and opposite sides of the plate articles to be held by the clamp, one of said jaws being normally substantially in contact with the plate throughout the inside face of said jaw and the other jaw being mostly considerably spaced from the opposite face of the plate whereby to provide ample space for the reception of a thick 90 supporting member. 95

In witness whereof, I hereunto subscribe my name to this specification.

MERRILL M. BLACKBURN.
